SEPARATING MERCAPTANS

John A. Brooks, Chicago, Ill., and Jack H. Krause,
 Theodore B. Tom, and Nathan Fragen, Ham-
 mond, Ind., assignors to Standard Oil Com-
 pany, Chicago, Ill., a corporation of Indiana

Application December 11, 1948, Serial No. 64,802

10 Claims. (Cl. 260—609)

1

This invention relates to a process of removing mercaptans from sour hydrocarbon oils and more particularly from petroleum distillates such as heavy napthas and heater oils. The invention is especially applicable to the refining of heater oils from which the mercaptans have heretofore been very difficult to remove because of their high molecular weight and correspondingly high oil solubility. Still more specifically the invention relates to a method of recovering caustic and methanol solutions employed in the extraction of mercaptans with a mixture of strong caustic alkali and methanol.

One object of the invention is to provide a method for more efficiently and more economically recovering the caustic-methanol solution employed in the extraction of mercaptans from sour petroleum distillates. Another object of the invention is to process the spent caustic solution containing mercaptans in such a manner that the mercaptan re-entry value of the regenerated caustic solution and caustic-methanol mixture is lower than has heretofore been economically possible. As a result of the lower mercaptan re-entry value of the recycled caustic-methanol solution, a more complete removal of mercaptans from the petroleum distillate is effected. Still another object of the invention is to recover caustic-methanol solutions which have been contaminated with mercaptans without subjecting the mercaptans to high temperature resulting in decomposition to hydrogen sulfide.

It has heretofore been the practice in extracting mercaptans from oils with caustic-methanol solutions to regenerate the caustic solution by stripping the mercaptans therefrom. When treating stocks containing low-boiling mercaptans, it has been relatively easy to remove the mercaptans from the caustic by the action of steam, particularly if the steam is superheated. With the higher-boiling mercaptans from kerosene and heater oil, however, removal from the caustic by distillation is not accomplished so readily and large amounts of steam are required, thus considerably increasing the cost of the recovery operation. Also, we have found that the use of temperatures of 250–300° F. and higher is required, which results in decomposition of mercaptans in the presence of strong caustic with formation of H₂S which neutralizes an equivalent amount of KOH, destroying its usefulness in the process. The removal of the mercaptans from the caustic by distillation also requires that the methanol be distilled off either with the mercaptans or in a preliminary distillation operation.

The methanol recovered in this way is generally contaminated by mercaptans unless special measures are adopted for purifying it.

We have now discovered that both the methanol and the caustic may be recovered almost free of mercaptans by the simple expedient of diluting the spent caustic methanol solution with water, providing that a highly concentrated caustic solution is used for extraction and the amount of dilution or regeneration is controlled within a specified water-concentration range. It is also desirable that a small amount, e. g. 0.2 to 5 per cent. of phenols, cresols or "xyleneols" be present in the solution to facilitate mercaptan separation. The term "xyleneols" will be used herein to designate higher boiling phenols which boil at about the boiling point of the cresols and the xyleneols or somewhat higher. Such xyleneols as occur naturally in petroleum distillates, especially the cracking still distillates, are well suited for our process. A typical xyleneol fraction extracted from heater oil had a boiling range of about 375 to 550° F.

The solutions employed should contain about 15 to 75 volumes of methanol for each 100 volumes of concentrated aqueous caustic employed, corresponding to about 5–30% by weight. Usually about 25 to 50 volumes of methanol are used per 100 volumes of aqueous caustic. After dilution, the spent solution is allowed to stratify in a settling chamber, preferably at a somewhat elevated temperature of the order of 80 to 140° F. The mercaptans and xyleneols separate from the solution predominantly in the form of their alkali metal salts, mercaptides and xyleneolates. The caustic solution containing the methanol is then reconcentrated to remove the added water and is ready for recycling to the process. It is preferred to use KOH because of its greater solubility and freedom from crystallization at high concentrations, altho NaOH can be used with careful control of concentration and temperature. Concentrations of about 50 to 65 per cent, based on the KOH-water components, are desirable.

The invention is illustrated by drawings in which—

Figure 1 is a graph showing the effect of water addition to a spent caustic solution with respect to the amount of xyleneolates and mercaptides discharged from the solution and the mercaptan number of the diluted caustic-methanol solution. The mercaptan number, sometimes called the copper number, is the milligrams of mercaptan sulfur per 100 ml. of oil, generally deter-

mined by titration with a standardized copper salt solution.

Figure 2 is a diagrammatic representation of a plant for carrying out the process.

In one series of experiments, a West Texas heater oil having a mercaptan number of about 60 was extracted with 55 per cent KOH solution containing twenty-five volumes of methanol and five volumes of potassium cresylates per 100 volumes of KOH solution. The ratio of caustic-methanol to heater oil employed in the extraction was 1:5 by volume. To the spent caustic solution containing mercaptans extracted from the heater oil there was added varying amounts of water and, after thorough agitation, the solution was allowed to settle for two hours. The aqueous layer was drawn off the bottom and analyzed for mercaptan content. The volume of the upper xylenolate-mercaptide layer was determined. The results are shown in the chart in Figure 1. The mercaptan number of the spent caustic solution before adding water was 288.5. It will be observed that this dropped to a value of about 20 after adding from about 30 to 100 volumes of water per 100 volumes of the spent caustic-methanol solution. Addition of more water beyond about 140 volumes caused an increase in the mercaptan number of the caustic layer, showing that a maximum amount of mercaptans is separated at a concentration corresponding to about 30 to 140 volumes of added water per 100 volumes of spent KOH solution. Expressed on the basis of percentage of water, this corresponds to about 55 to 72 per cent, based on the KOH and water components of the solution alone.

In our preferred operation, the amount of water added should be at least about twice the weight of the methanol in the spent solution and less than the weight of KOH present.

Referring to Figure 2, the process is carried out in the following manner: The sour hydrocarbon distillate, for example, heater oil containing mercaptans, is supplied to the system by line 10 leading to mixer 11 where it is contacted with a caustic solution, e. g. NaOH, primarily to remove H_2S as well as other strongly acid constituents. A caustic solution of about 5 to 15 per cent is adequate for this purpose. From the mixer 11 the stock passes to settler 12 from which the caustic solution is recycled by line 13 and pump 14. From time to time spent caustic can be removed from the system by drawoff line 13a and fresh caustic supplied by line 15.

From prewash settler 12 the distillate is conducted by line 16 to mixer 17 where it is contacted with caustic-methanol solution for removal of mercaptans. A satisfactory solution may contain about 55 per cent KOH based on the water plus KOH present, and in addition thereto about 25 volumes of methanol per 100 volumes of aqueous KOH solution. From mixer 17 the distillate passes to settler 18 where the caustic-methanol solution is allowed to separate from the distillate. Line 19 then conducts the distillate to mixer 20 where it is contacted with fresh caustic-methanol solution introduced by line 21. The distillate then passes to settler 22 where the caustic-methanol solution is again separated by gravity and withdrawn by line 23 leading to mixer 17, thus effecting a countercurrent extraction of mercaptans by the caustic-methanol solution. Altho only two countercurrent stages are shown, more countercurrent stages may be employed, e. g. 3 to 5 stages, and if desired a countercurrent

tower contactor may be employed in lieu of the stage extraction system.

From settler 22 the extracted distillate, which may be substantially free of mercaptans or have a low mercaptan number of about 2 to 5, passes by line 24 to mixer 25 where it is contacted with water for the removal of small amounts of entrained caustic not separated in settler 22 and for the removal of a small amount of dissolved methanol. Water for the purpose may be added to the system by line 26 and it is preferred that water for this purpose be free of CO_2 which has the undesirable effect of partially neutralizing the caustic. From mixer 25 the distillate flows to settler 27 whence the finished sweetened distillate is withdrawn by line 28. Water settled in 27 is recycled by line 29 back to mixer 25.

Caustic-methanol solution contaminated with mercaptans, having a mercaptan number of about 200 to 400, is withdrawn by line 30 and conducted to mixer 31 where it is intimately contacted with a carefully regulated amount of water introduced by line 32. The amount of water must be sufficient to reduce the solubility of mercaptides and xylenolates to a low value and cause them to separate from the caustic-methanol solution, but an excessive amount of water must be avoided to prevent re-solution of the mercaptides and xylenolates. The addition of about 20 to 180 volumes of water per 100 volumes of the spent caustic-methanol solution previously described is satisfactory, from 30 to 90 volumes being a preferred amount.

From mixer 31 the diluted caustic-methanol solution passes to settler 33 where the xylenols and mercaptans in the form of their alkali metal compounds, potassium xylenolates and potassium mercaptides, separate as an upper layer which is a liquid and can be withdrawn from settler 33 by line 34. The caustic-methanol solution, substantially free of mercaptans, is withdrawn by line 35 and charged to still 36 where it is reconcentrated for re-use in the system. Heat for still 36 can be furnished by reboiler 37. Vapors of methanol and water are conducted by line 38 to methanol fractionator 39 where the methanol is separated from the water, methanol vapors being withdrawn overhead by line 40 leading to condenser 41 and receiver 42. Water is withdrawn from the base of 39 by line 43 and recycled to mixer 31 for further use in the system. Because all the water can be re-used in the system, it is not necessary to completely separate methanol from water in fractionator 39.

Alternatively, removal of water from the caustic solution can be effected at a lower temperature by first distilling off methanol from the caustic solution, employing a moderate vacuum, if desired, to reduce the temperature required, then, in a second distillation stage, removing water under relatively high vacuum, e. g. 10 to 50 mm. mercury pressure, absolute. By this method, discoloration of the caustic solution from heating is still further reduced and the methanol fraction recovered in the first distillation stage is sufficiently free of water to be recycled to the extraction step without further fractionation.

A part of the water stream from line 43a may be periodically conducted, e. g., via line 25 by connections not shown to the final water-washing stage 27 of the extraction system. When the amount of methanol and entrained KOH collected in 27 is sufficient to require replacing the water therein, it can be withdrawn periodically by

pump 45 and lines 44 and 32 leading to mixer 31. Reconcentrated KOH solution from still 36 is withdrawn by lines 46 and 47 to mixing chamber 48 wherein it is mixed with methanol drawn from receiver 42 by line 49. The caustic-methanol solution in chamber 48 is mixed to the desired composition and recycled to the extraction system by lines 50 and 21 as hereinabove described.

The separation of mercaptides from the caustic solution in separator 33 is considerably facilitated by the presence of cresols, xylenols and higher molecular weight hydroxy aromatic compounds such as those normally occurring in petroleum distillates, particularly in higher boiling distillates such as heater oils. These acidic phenolic substances are herein referred to as xylenols and their alkali metal salts as xylenolates. The amount naturally present in heater oils, about 0.05 per cent, is usually sufficient to bring about a rapid separation of the alkali metal mercaptides from the caustic solution after water dilution in 33. Additional xylenols may be added to the system by line 51, if desired, or by adding them directly to the stock treated. Furthermore, xylenols may be recycled in the system as will be hereinafter described.

The upper oily layer of mercaptides and xylenolates withdrawn by line 34 from separator 33 contains both combined and entrained caustic alkali which may be discarded by line 34a but which it is generally desirable to recover and recycle to the system. This may be accomplished in various ways, the following method being illustrated in the drawing: The mercaptide-xyleneolate stream is heated by steam heater 52 or by steam injected thru line 53. Water may also be added, if desired, to increase the dilution. After thoro mixing, the mixture is allowed to settle in settler 54, generally maintained at an elevated temperature and under pressure to increase the extent of hydrolysis. Oil or other solvent may be added to the mixture in separator 54 if desired, to assist separation of the hydrolyzed mercaptans from the caustic alkali solution. Mercaptans are withdrawn by line 55 continuously or periodically. The aqueous caustic solution containing some mercaptans and xylenols is conducted by line 56 to stripper 57 where most of the remaining mercaptans are stripped out by steam introduced by line 58. Additional heat may be supplied to the base of stripper 57 by reboiler 59. The mercaptans together with steam and a small amount of residual methanol vapors are conducted by vapor line 60 to condenser 61 and receiver 62 from which the mercaptans are withdrawn by line 63. The dilute aqueous methanol-caustic solution collecting in 62 is conducted by line 64 to the methanol fractionator 39. To prevent appreciable amounts of xylenols from being carried overhead with the vapors from 57, a small stream of caustic alkali solution may be introduced by line 65 into the top of stripper 57. For this purpose, caustic solution from settler 33 may be bypassed thru line 66 or it may be withdrawn by line 67 from the base of methanol stripper 36.

The caustic solution collecting in the bottom of stripper 57 together with alkali metal xylenolates is withdrawn by line 68 and recycled to the system by line 69. The amount of mercaptans carried back into the system in this way is relatively small, depending on the efficiency of the stripping operation conducted in 57. The mercaptan number of the recovered xylenolates is usually under 1000 and since the amount of this recycled stream is very small, this is not sufficient

to adversely affect the extent of mercaptan removal from the oil treated in extractors 18 and 22. Thus the volume of the recycled xylenol-KOH stream in line 69 may be only 1 to 10 per cent of the volume of the main caustic-methanol solution in line 47.

When operating with stocks which are relatively high in their content of xylenols, it is sometimes desirable to eliminate partly or entirely the xylenolates from the system by line 70. When treating lighter hydrocarbon stocks such as sour kerosene and heavy naphtha, it is preferred to add to the system the xylenols or other mercaptan solvent extracted from a higher boiling stock such as heater oil, in order to increase the extent of the mercaptan separation in 33. Likewise, other mercaptan solvents may be employed for this purpose such as Cellosolve, tributylamine, octyl and nonyl amines, lauryl alcohol, and other high-boiling alcohols and ethers which are normally liquids. These solvents may be recovered in a manner similar to that described and recycled in the system.

As an example of an operation employing our process, 3000 ml. of spent caustic-methanol solution prepared from 55 per cent aqueous KOH and 25 volumes of methanol per 100 cc. KOH solution were diluted with 900 ml. of water. The spent KOH-methanol solution had a mercaptan number of 513 which corresponded to 15.4 grams of sulfur. The total weight of KOH in solution was 1865 grams. After dilution, there separated from the solution 480 ml. of mercaptide layer containing 13.7 grams of mercaptan sulfur determined by analysis. The remaining caustic solution measuring 3420 ml. had a mercaptan number of 50 corresponding to only 1.71 grams of mercaptan sulfur. This solution was subjected to stripping with steam, methanol and water being removed as a distillate for further separation. The remaining regenerated KOH solution of 55 per cent KOH concentration was suitable for recycling after the addition of the proper amount of methanol.

The oily mercaptide layer from the dilution step, measuring 480 ml., was further diluted and heated with 960 ml. of water. On standing, it separated into two layers. An upper mercaptan layer measuring 190 ml. had a mercaptan number of 6650 corresponding to 12.64 grams of sulfur. The amount of KOH remaining in this mercaptan layer was only 0.22 gram by analysis. The remaining solution measuring 1250 ml. contained substantially all the methanol and KOH originally present in the mercaptide layer and was suitable for recycling to the dilution step for treatment in other ways for recovery of methanol and KOH.

Another method for recovering methanol and caustic from the alkali mercaptides and xylenolates separated in settler 33 can be employed with considerable simplification. According to this method, sufficient water and/or steam is added by line 53 to substantially entirely decompose the alkali mercaptides and xylenolates in settler 54. Hydrolysis of these materials is facilitated by operating at elevated temperature, for example 300 to 400° F. under pressure. Hydrolysis is also greater when operating with the higher boiling stocks which yield mercaptans and xylenols of higher molecular weight.

When operating by this simplified method, the aqueous solution of caustic alkali and methanol is withdrawn from the bottom of separator 54 by dotted line 71 and conducted directly to mixer

31 where it is employed for diluting the spent caustic stream from the extraction system. When operating according to this method, it is not necessary to provide stripper 57 and accessories including lines 64, 65 and 69.

Our process enables substantially all the caustic and methanol to be recovered substantially without mercaptan contamination by the simple expedient of diluting with water and settling or centrifuging. The simplicity of the operation 10 will be quite apparent. After dilution and separation of the mercaptans, it is only necessary to eliminate the excess water from the caustic solution before it can be recycled in the system.

Having thus described our invention what we 15 claim is:

1. The process of removing mercaptans from a concentrated caustic-methanol solution consisting essentially of an alkali metal hydroxide solution in aqueous methanol which process comprises diluting the solution with an amount of water sufficient to effect separation of the solution into an aqueous caustic-methanol phase and an oily mercaptide phase and separating said mercaptide phase from said aqueous caustic-methanol phase.

2. The process of claim 1 wherein said caustic-methanol solution contains about 10 to 50 volumes of methanol per 100 volumes of aqueous caustic.

3. The process of claim 1 wherein the separation of mercaptans from the diluted caustic-methanol solution is facilitated by the presence of a mercaptan solvent insoluble in the aqueous caustic-methanol phase resulting from dilution with water.

4. The process of claim 3 wherein said mercaptan solvent consists essentially of xylenols.

5. The process of removing mercaptans from a sour petroleum distillate oil higher boiling than gasoline which comprises extracting said mercaptans with a solution of KOH containing about 50 to 65 parts by weight of KOH and 50 to 35 parts of water respectively and, in addition, about 15 to 75 volumes of methanol per 100 volumes of aqueous KOH, separating the extract containing mercaptans from said distillate, diluting the extract with sufficient water to effect separation into two phases, an aqueous KOH-meth-

anol phase and an oily mercaptide phase, separating said phases, removing water from said aqueous KOH-methanol phase to restore it to the concentration first described hereinabove and recycling it to the extraction step for removal of mercaptans from further quantities of petroleum distillate.

6. The process of claim 5 wherein said oily mercaptide phase is hydrolyzed with water to recover therefrom an aqueous solution of KOH and methanol.

7. The process of claim 6 wherein said aqueous solution of KOH and methanol is recycled to said dilution step instead of the water used therein.

8. The process of claim 6 wherein said aqueous solution of KOH and methanol is distilled to remove water therefrom and the recovered KOH and methanol is recycled to said distillate extraction step.

9. The process of removing mercaptans from a solution of KOH, water and methanol in which the weight of KOH is at least equal to the weight of water present and the methanol constitutes about 5 to 30 per cent of the weight of the solution which comprises adding to the solution an amount of water equal to at least about twice the weight of methanol and less than the weight of KOH, thereby effecting separation of an insoluble potassium mercaptide layer and separating said potassium mercaptide layer from the aqueous KOH-methanol solution.

10. The process of claim 9 wherein xylenols are added to the mercaptan-contaminated KOH-methanol solution to assist the separation of said potassium mercaptides.
